HAND-OPERATED PRESSURE OILCAN

Chester A. Anderson, Litchfield, Minn., assignor
of one-third to Alfred Anderson and one-third
to Raymond N. Ornberg, both of Litchfield,
Minn.

Application September 27, 1946, Serial No. 699,907

13 Claims. (Cl. 222—378)

1

This invention relates to hand oilers of that type which includes a pump which is actuated by the fingers to eject oil from the can.

The present invention is an improvement upon the structures disclosed and claimed in my prior Patents Number 2,169,209, issued August 15, 1939, and No. 2,299,450, issued October 20, 1942.

It is an object of the present invention to provide a hand operated pressure oil can which is conveniently constructed of several parts providing a cylinder and piston unit, a spout shiftable with the piston and a finger pressure element supported in association with the spout whereby the entire assembly can be inserted in and removed from the can proper as a unit.

Another object of the invention is to provide an improved piston or plunger unit having therewith a piston guiding portion and a spout supporting portion which latter portion includes means for advantageously securing and supporting the finger pressure element.

Another object of the invention is to provide a pressure oil can wherein the movable piston assembly and its cooperating parts are effectively sealed to prevent leakage from the can body and about the lower portion of the spout.

Still another object of the invention is to provide a pressure oil can unit including a spring pressed piston or plunger wherein adequate thrust receiving means is included to limit the spring induced movement of the piston assembly.

The above and other objects and advantages of the invention will more fully appear from the following description made in connection with the accompanying drawings, wherein like reference characters refer to the same parts throughout the views, and, in which:

Figure 1 is a view partially in side elevation and partially in vertical section of an embodiment of the invention;

Figure 2 is a section taken approximately on the line 2—2 of Figure 1 with the can body cap removed;

Figure 3 is a fragmentary vertical sectional view through another form of the invention; and

Figure 4 is a fragmentary vertical sectional view through still another form of the device.

In Figure 1 there is shown a can body 5 having an externally threaded mouth portion 6, the mouth opening being defined by a rolled edge 7.

Resting upon the rolled edge of the can mouth 7 is a gasket 8 and on top of the gasket is an annular flange 9 forming the upper portion of a cup-shaped cylinder 10 having a closed bottom 11. The side wall of the cylinder 10 is provided with

15 apertures 12 which provide liquid flow communication between the interior of the cylinder 10 and that of the can body 5.

A piston head 13 is located in the cylinder 10 said head having an outer flanged portion 14 and an inwardly concentric parallel flange 15 defining a central opening in said piston 13. A compression spring 16 has its lower end mounted about an upwardly pressed central portion 17 of the lower end 11 of the cylinder 10, and the upper end of the spring 16 bears against the horizontal under side portion of the piston 13 between the flanges 14 and 15.

15 Threaded upon the threaded portion of the can mouth area is a centrally apertured cap 18, said aperture being defined by a downwardly turned flange 19. The cap 18 is provided with a downwardly facing concave portion 20 for a purpose to be described below.

A tapered spout 21 extends downwardly through the aperture in the cap 18 and through the central aperture in the piston 13. A circumferential rib 22 near the bottom of the spout 21 limits downward movement of said spout through the apertured piston 13 and the extreme lower portion of said spout 21 is bent upon itself as at 23 to grip the inner concentric flange 15 of the piston 13. Consequently, the piston 13 and spout 21 are connected and held against relative axial movement.

It will be noted that the piston 13 has an outer diameter which is somewhat less than the inner diameter of the cylinder 10. Interposed between the outer flange 14 of the piston 13 and the inner cylinder side wall 10 is a cylindrical portion 24 of a combined piston guiding and spout supporting unit indicated generally at 25. The cylindrical portion 24 of the unit 25 closely fits on the piston 13 and has sliding engagement with the inner side wall of the cylinder 10. Above the cylindrical portion 24 is a reduced cylindrical portion 26 which is spaced some distance from the cylinder wall to receive a packing element 27 a portion of which is closely fitted between said reduced cylindrical portion 26 and the inner side wall of said cylinder 10. Another portion of the packing element 27, as is clearly shown, extends over a shoulder 28 formed by a further reduction of the diameter of the upper portion of the guiding and supporting unit 25. The upper and third cylindrical or tubular reduction 28 of the guiding and supporting element 25 closely engages a portion of the spout 21 as shown.

About the smallest reduced portion 28 of the unit 25 is a tubular element 29 which extends

downwardly between the tubular or cylindrical section 28 of said member 25 and the downwardly turned flange 19 defining the opening in the cap 18. Thence the element 29 is bent outwardly and its outer edge is curved downwardly as at 30. The bent portion 30 is adapted to abut the portion 20 of the under surface of the cap 18 to provide a thrust receiving member so that the downwardly turned flange 19 defining the central opening through the cap 18 will not be subjected to all of the thrust exerted by the spring 16, and as a result wear of the above mentioned parts is practically limited. It will be noted that the contact area between the curved flange portion 30 on the bottom of the outer tubular element 29 is considerably greater than the downwardly turned edge of the flange 19.

It will also be seen that the upper portion of the packing element 27 which lies about the shoulder 28 on the guiding and supporting unit is clamped between said shoulder on said guiding and supporting unit and the curved flange portion 20 on the tubular element 29. If desired the outwardly turned lower portion of the tubular element 29 may be provided with one or more downwardly dimpled portions 29a shown in Figures 1 and 2 to more firmly grip the packing element 27.

Mounted on the upper portions of the tubular sections 28 and 29 is a collar or flange 31 having a central aperture defined by an upwardly turned flange 32. The finger pressure element 31 rests upon the upper end of the outer tubular section 29, and the upper portion of the inner tubular section 28 is bent over upon the flange 32 as shown at 33 and against the upper side of the finger pressure element 31 to not only engage the flange 32 but also to grip the finger pressure element 31 between said turned-over portion and the upper end of the outer tubular element 29.

The device above described is so constructed that when assembled it provides an extremely sturdy, easily operated, non-leaking pump unit for pressure oil cans. When the cap 18 is unscrewed from the threaded portion 6 of the can mouth the entire pump unit and spout assembly can be removed from the can and all of the parts of the construction except the can proper are kept together without having any of the parts become separated from others. At the same time, however, the assembly of the device is relatively simple. The assembly requires no securing devices such as soldering, welding or bolts, but at the same time it is firmly held with its parts in their proper positions relative to each other. It is rather clear from the disclosure in the drawing that when the finger pressure element is pressed downwardly it will carry the spout 21, piston 13 and piston guiding and spout supporting unit 25 as well as the packing and the outer tubular element 29 downwardly relative to the can cap 18 and cylinder 10. Oil can flow through the openings 12 to the bottom of the cylinder 10 and when the lower edge of the outer flange 14 on the piston 13 passes below said openings 12 in the cylinder wall oil in the lower portion of the cylinder will be forcibly ejected through the spout 21. Naturally, if the level of oil in the can body 5 is below the openings 12 the can must be tilted so that oil will flow into the cylinder 10.

In Figure 3 there is shown another form of the invention which includes some of the parts shown and described in connection with Figure 1.

The can body 5 and its threaded mouth por-

tion 6 as well as the threaded cap 18 are the same as in Figure 1. Also the same structure is shown in the cylinder 10, the compression spring 16 and the piston 13 with its connection with the bottom end of the spout 21.

There is a cylindrical section 34 which lies between the outer flange of the piston 13 and the inner side wall of the cylinder 10. Extending upwardly therefrom is a reduced cylindrical section 35 which is spaced inwardly from the inner wall of the cylinder 10 similar to the reduced cylindrical section 26 shown in Figure 1. A shoulder 36 similar to the shoulder 28 is formed by an inwardly extending portion 37 at the top of the reduced cylindrical section 35 and a downwardly turned flange 38 at the inner edge of the horizontal portion 37 defines a central opening. A packing element 39 has a portion lying between the reduced cylindrical section 35 and about the shoulder 36 as is clearly indicated.

The cap 18 is provided with an upwardly offset portion 18a into the under side of which is fitted a ring 40 which provides an element having considerable contact area adapted to engage the under side of the cap 18 to relieve the pressure and wear upon the flange 19 which defines the central opening of said cap 18 as described in connection with Figure 1. The ring 40 overlies the inwardly turned portion of the packing element 39 and as in the case of the structure shown in Figure 1 provides with said packing element a yielding thrust transmitting member adapted to contact the under side of the cap.

Extending upwardly through the central opening in the cap 18 is a tubular element 41 whose lower end 42 is shown bent about the downwardly turned flange 38 defining the opening in the upper portion of the composite element 34, 35, 37. A short distance above the bent-over lower end 42 of the tubular element 41 said tubular element is enlarged to provide a shoulder 43 which clamps the ring 40 between said shoulder 33 and the turned-over lower end 42 of the tubular element 41. The upper portion of the tubular element 41 is reduced in thickness and offset to provide a shoulder 44 upon which rests a centrally apertured finger pressure element 45. That portion of the finger pressure element 45 defining its central opening is provided with an up turned flange 46 over which the reduced upper end 47 of the tubular element 41 is bent, thereby clamping the finger pressure element 45 between said over-turned upper end of the tubular element 41 and its shoulder 44. At the same time the upper inner diameter of the reduced end 47 of the tubular element 41 is such as to firmly engage the outer wall of the spout 21 so that it will be rigidly held in place.

In Figure 4 there is shown a third form of construction embodying the general features of the invention shown in Figures 1 through 3. The can body 5 and cap 18 are the same as in the other constructions, and the cylinder 10, the piston 13 and spring 16 are also the same. The spout 21 extends through the can cap 18 in the same manner as above and it is clamped to the inner flange 15 of the cylinder 10 in the same manner. There is the element with its cylindrical portion 34 lying between the outer piston flange 14 and the inside of the cylinder wall and the upward extension of the cylindrical member 34 is reduced as at 26 in the other forms.

Lying about a portion of the spout 21 and extending through the opening in the can cap 18 is a tapered sleeve 48 whose lower end is bent

about an inwardly concentric flange 49 lying parallel to the reduced cylindrical portion 26. A packing element 50 has a portion lying between the reduced cylindrical portion 28 and the cylinder wall 10 and another portion thereof overlying the shoulder 51 at the upper end of the reduced cylindrical portion 26. A somewhat reversely curved packing retaining ring 52 overlies the horizontal portion of the packing element 50 and as is shown in Figure 4 the upper portion of the packing retainer ring 52 abuts a substantial area of the underside of the can cap 18 in a manner similar to the curved flange 30 on the bottom of the outer tube or sleeve 29, as viewed in Figure 1. However, in Figure 4 the packing retainer ring and thrust absorbing member 52 is an entirely separate piece of material. It is held down against the packing by the downwardly turned portion 19 of the cap 18 which defines the central opening in said cap.

The upper end of the tapered tubular element 48 has its upper end turned over as at 53 to engage an upwardly turned flange 54 on a centrally apertured finger pressure member 55. A shoulder 56 is formed at the bottom of the upwardly turned flange 54 on the finger pressure member 55 and an outer tapered sleeve 57 extends through the aperture cap 18 to engage the inner edge of the packing retaining and thrust absorbing ring 52, and said sleeve extends upwardly to engage the shoulder 56 on the finger pressure element 55.

In the structures shown in the drawing it will be seen that I have provided an oil can having a reciprocating piston or plunger operated by a firmly fixed finger pressure element mounted on the spout or adjacent thereto and wherein efficient packing means and packing retaining means is provided, a portion of the packing retaining means being so positioned relative to the under side of the can cap that upward thrust of the compression spring 16 is made by a relatively broad surface contact by a packing retainer element and the under side of the cap. This greatly reduces wear on the relatively movable parts which are urged together by the spring and increases the effective life of the device. The movable piston and bottom of the dispensing spout are assembled in a relatively simple yet permanently firm manner and each of the units thereof made up of several parts is held together so that the entire pump and spout unit with the finger pressure element and the can cap can be quickly and easily removed from the can for cleaning purposes, and all of said parts are interconnected so that they are retained as a unit, and can be just as easily inserted in the can and fastened to the can mouth by means of the cap. As stated above, all of the parts are interconnected without having to resort to the use of welding, soldering or bolting or other connecting means other than the bending of one metal part upon the other or the clamping of one metal part between two others. The elements 24 in Figure 1 and 34 in Figures 3 and 4 which lie between the piston proper and the inner wall of the cylinder provide relatively long wearing guide means for the piston and spout while at the same time a highly efficient type of packing is provided to prevent the escape of oil from the can body without imposing too much wear on the same. The device is easily operated with one hand and by reason of the structure shown and claimed the parts will work easily and not become jammed.

It will, of course, be understood that various changes may be made in the form, details, arrangement and proportions of the various parts without departing from the scope of my invention.

What I claim is:

1. In a pressure oil can, a can body having a mouth, a pump cylinder supported in said mouth and having its interior in flow communication with the interior of said can body, a piston movable in said cylinder, a spout connected to said piston and communicating with the interior of said cylinder, said spout extending upwardly through the mouth of said can body, a combined piston guiding and spout supporting unit, a portion of said guiding and supporting unit lying between said piston and the inner wall of said cylinder and in sliding contact with said wall, another portion of said guiding and supporting unit being spaced inwardly from the inner wall of said cylinder, and a packing element interposed between said second mentioned portion of said guiding and supporting unit and the inner wall of said cylinder.
2. The structure in claim 1, and said guiding and supporting unit having an upwardly disposed shoulder, a portion of said packing element being disposed inwardly over said shoulder, an apertured cap lying about said spout and removably received on said mouth of said can body, and a thrust transmitting element interposed between the inwardly disposed portion of said packing element and the under side of said cap.
3. In a pressure oil can, a can body having a mouth, a pump cylinder supported in said mouth and having its interior in flow communication with the interior of said can body, a piston movable in said cylinder, a spout connected to said piston and communicating with the interior of said cylinder, said spout extending upwardly through the mouth of said can body, a combined piston guiding and spout supporting unit having lower and intermediate portions of different diameters, said lower portion being of greater diameter than said intermediate portion and lying between said piston and the inner wall of said cylinder in sliding contact with the latter, and a packing element located between the intermediate portion of said guiding and supporting unit and the inner wall of said cylinder.
4. The structure in claim 3, and an apertured cap through which said spout extends, said cap being removably secured in said can body and over the mouth thereof, and a portion of said packing element being interposed between a portion of said guiding and supporting unit and said cap.
5. In a pressure oil can, a can body having a mouth, a piston and cylinder assembly supported in said mouth, a spout extending from said piston and cylinder assembly and through said mouth, said piston and cylinder assembly including a spring normally urging said piston toward said mouth, an apertured cap on said mouth and through which said spout extends, that portion of said cap defining said aperture having a downwardly turned edge positioned to contact said piston when urged upwardly by said spring, and the under side of said cap having a second piston contact area.
6. The structure in claim 5, and said second piston contact area of said cap being considerably greater than that of said downwardly turned edge defining the aperture in said cap.
7. In a pressure oil can, a can body having a

mouth, a cylinder supported in said can body, a piston unit movable in said cylinder, a spring normally urging said piston unit in one direction in said cylinder, a spout extending outwardly from said piston, said piston unit having a pair of generally concentric, upwardly disposed tubular elements thereon, said spout being closely fitted in the inner of said tubular elements, the outer of said tubular elements being spaced outwardly from the intermediate and upper portions of the inner tubular element, and an apertured finger pressure element, that portion of said finger pressure element defining its aperture being secured between the upper portions of said upward tubular elements and said piston unit.

8. The structure in claim 7, and the inner of said upward extensions having a greater height than the outer extension, said apertured finger pressure element fitting closely about said inner tubular extension and lying on the upper edge of said outer tubular extension, and the upper portion of said inner tubular extension being turned over upon the upper side of said finger pressure element to grip said element between said turned-over portion of said inner extension and the upper edge of said outer extension.

9. In a pressure oil can, a can body having a mouth, a cylinder supported in said can body, a piston unit movable in said cylinder, a spout connected to said piston unit and extending outwardly from said cylinder and can mouth, said piston unit including an upwardly generally tubular element having an upper portion defining an aperture through which said spout extends, a second tubular element having its lower end bent upon the aperture defining portion of the upper part of said first mentioned tubular piston unit element, said second tubular element having an upwardly directed shoulder adjacent its upper end, an apertured finger pressure element lying about the upper portion of said tubular element and resting on said shoulder, and a portion of said upper end of said second tubular element being bent over on said aperture defining portion of said finger pressure element.

10. In a pressure oil can, a can body having a mouth, a cylinder supported in said can body, a piston unit movable in said cylinder, a spout connected to said piston unit and extending outwardly from said cylinder and can mouth, said piston unit including an upward generally tubular element having an upper end portion defining an aperture through which said spout extends, a second tubular element having its lower end bent upon the aperture-defining portion of the upper part of said first mentioned tubular piston unit element, said second tubular element being in contact with said spout throughout substantially its entire length, a finger pressure element lying about the upper portion of said second tubular element, and said upper portion of said second tubular element being bent over upon said finger pressure element.

11. The structure in claim 10, and a third tubular element lying about said second tubular element, the lower portion of said third tubular

element resting upon said piston unit, and the upper end of said third tubular element being in contact with the underside of said finger pressure element.

- 5 12. In a pressure oil can, a can body having a mouth, a pump cylinder supported in said mouth and having its interior in flow communication with the interior of said can body, a piston movable in said cylinder, a spout connected to said piston and communicating with the interior of said cylinder, said spout extending upwardly through the mouth of said can body, a combined piston guiding and spout supporting unit, a portion of said guiding and supporting unit lying 10 between said piston and the inner wall of said cylinder, another portion of said guiding and supporting unit extending upwardly through the mouth of said can body and engaging said spout above said can body, a finger pressure element 15 mounted on said upwardly extending portion of said guiding and supporting unit, and said cylinder, piston, spout, piston guiding and supporting unit and finger pressure element being removable from said body as a unit.
- 20 13. In a pressure oil can, a can body having a mouth, a pump cylinder supported in said mouth and having its interior in flow communication with the interior of said can body, a piston movable in said cylinder, a spout connected to said piston and communicating with the interior of said cylinder, said spout extending upwardly through the mouth of said can body, a combined piston guiding and spout supporting unit, a portion of said guiding and supporting unit lying 25 between said piston and the inner wall of said cylinder, another portion of said guiding and supporting unit extending upwardly through the mouth of said can body and engaging said spout above said can body, an apertured cap removably secured on said can body mouth, said spout and a portion of said guiding and supporting unit extending through said cap and being vertically movable relative to said cap, a finger pressure element mounted on said upwardly extending 30 portion of said guiding and supporting unit, a compression spring interposed between a portion of said cylinder and the underside of said piston to yieldably urge said piston, spout, and guiding and supporting unit upwardly, and said cap overlying a portion of said guiding and supporting unit to limit the spring urged upward movement of said cylinder, spout, and guiding and supporting unit.
